UNITED STATES PATENT OFFICE.

WILBER THOMAS, OF QUINCY, ILLINOIS.

DESIGN FOR A FENCE-PICKET.

SPECIFICATION forming part of Design No. 12,972, dated June 13, 1882.

Application filed April 20, 1882. Term of patent 14 years.

To all whom it may concern:

Be it known that I, WILBER THOMAS, of Quincy, in the county of Adams and State of Illinois, have invented and produced a new and original Design for Fence Pickets, Palings, and the like; and I do hereby declare that the following is a full, clear, and exact description of the invention, which will enable others skilled in the art to which it appertains to make and use the same, reference being had to the accompanying drawings, which form a part of this specification.

In the drawings, Figure 1 is a perspective view of a picket embodying my improved design. Fig. 2 is a sectional view thereof, and Fig. 3 is a perspective view of a fence formed of my ornamental pickets.

Corresponding parts in the figures are denoted by like letters of reference.

This invention relates to designs for the pickets, palings, &c., of fences, and has for its object to secure novelty, attractiveness, and simplicity at but slight expense in manufacturing.

To this end it consists in certain improvements in the contour of the same, substantially as will be hereinafter more fully set forth.

Referring by letter to the drawings, A designates the picket, which is of simple elliptical shape in cross-section, with smooth rounded edges. The top B of the picket is curved in the shape of an arc, as shown, the ends of which arc connect with the rounded edges C of the picket, formed by its elliptical shape.

This ornamental picket is designed to be secured between the posts of the fence by longitudinal wires, as shown in Fig. 3, or any other suitable means, and thus impart to the fence a neat and attractive appearance.

I claim and desire to secure by Letters Patent—

The improved design for ornamental fence pickets, palings, and the like, herein shown and specified.

In testimony that I claim the foregoing as my own I have hereto affixed my signature in presence of two witnesses.

WILBER THOMAS.
